(57) **CLAIM**

The ornamental design for a lid for a sharps container, as shown and described.

DESCRIPTION

FIG. 1 is a perspective view of a lid for a sharps container, showing our new design;

FIG. 2 is a front view of the lid for a sharps container, which is identical to the rear view, the right side view, and the left side view;

FIG. 3 is a top view of the lid for a sharps container; and, FIG. 4 is a bottom view of the lid for a sharps container.
